UNITED STATES PATENT OFFICE

162,918

GATE TOP ORNAMENT

Bernard Youngworth, Baltimore, Md.

Application March 7, 1950, Serial No. 8,385

Term of patent 14 years

(Cl. D28—1)

To all whom it may concern:

Be it known that I, Bernard Youngworth, a citizen of the United States, residing at Baltimore city, State of Maryland, have invented a new, original, and ornamental Design for a Gate Top Ornament, of which the following is a specification, reference being had to the accompanying drawings, forming a part hereof.

I claim:
The ornamental design for a gate top ornament, as shown.

BERNARD YOUNGWORTH.
